Yiu Dak Chi, Kowloon, Hong Kong, assignor to Forda
Manufacturing Company Limited, Kowloon, Hong
Kong

Filed Aug. 28, 1968, Ser. No. 13,295

Term of patent 14 years

Int. Cl. D15—07

U.S. Cl. D49—13

FIG. 1

FIG. 5

FIG. 6

YIU DAK CHI.

FIG. 2

FIG. 3

FIG. 4

FIG. 1 is a perspective view of the vacuum cleaner for an automobile showing the design of the present invention;

FIG. 2 is a side elevation view thereof;

FIG. 3 is a top plan view thereof;

FIG. 4 is a bottom plan view thereof;

FIG. 5 is a front elevation view thereof; and

FIG. 6 is a rear elevation view thereof.

The broken lines are shown for illustrative purposes only.

I claim:

The ornamental design for a vacuum cleaner for an automobile, as shown and described.
